4 Claims

ABSTRACT OF THE DISCLOSURE

An intake control for disposal units mounted in a kitchen sink, and the like, that sits in the intake conduit of the disposal unit and has a lower member in which an outlet passageway is formed, an upper member mountable in said lower member, said upper member having perforations therein and an outlet valve and valve stem, said unit having means for sealing the discharge conduit, and being removable from said discharge conduit by merely lifting same out of the conduit intake opening.

SUMMARY OF THE INVENTION

A disposal intake control having a lower member adapted to seat in the upper end of a disposal conduit, and having a discharge opening in said lower member, and an outwardly projecting flange on the upper margin of said lower member, a yieldable member mounted on and covering said projecting flange, said lower member having internally threaded connecting means adjacent the upper end thereof, and an upper unit having a plurality of perforations, and having its upper surface threaded adjacent the lower margin of said member to be engaged with the threads of the lower member, and a manually operated valve in said upper unit adapted to seat in the discharge opening of the lower unit, said valve opening and closing the discharge conduit and the upper member restricting the size of particles passing into the disposal intake conduit.

The invention is more particularly described in the following specifications and illustrated in the accompanying drawings, wherein:

FIG. 1 is an exploded view of the unit, partially in cross section, and

FIG. 2 is an elevational sectional view of the device mounted in a disposal intake conduit.

In the drawings, the numeral 1 designates a sink in which the disposal unit conduit 2 is mounted. The lower member 3 is semi-spherical, and has the discharge opening 4 which is tapered inwardly, and which receives the valve 5 to close the discharge intake conduit 2. The upper margin of the member 3 has the outwardly projecting annular flange 6 upon which is mounted the resilient sealing member 7, the member 7 having the internal annular groove 8 adopted to receive the flange 6.

The upper end of the lower member 3 is internally threaded, as at 9, to receive the external threads 10 of the upper member 11. The upper member 11 has a plurality of drain openings, as 12, 12, of the desired size, and has the axial square valve stem opening 13. The valve stem 14, integral with the seat 5, is mounted in the upper member 11 through the square opening 13. The valve stem is square over the upper portion thereof as at 14, and is reduced and rounded as at 15, over the lowermost portion, and the valve 5 is mounted thereon as by the screw 17. An enlarged portion 16 forms the top, or grip, of the valve stem.

The assembled device may be readily mounted in the intake opening of the disposal conduit, the bottom por-

2

tion of the sealing member 7 resting on the internal shoulder formed on the inside of the intake disposal conduit, and the discharge opening 4 extending into said conduit beneath said shoulder. When it is desired to permit water and particles of matter in the water to flow into the disposal conduit, the valve stem is manually raised until the shoulder formed by the termination of the squared portion of the stem 14 passes the opening 13 in the top member, and the stem is turned into misalignment with said opening and the valve 5 thus held out of contact with the seat 4. When it is desired to block the flow of water through the discharge opening 4, the stem is aligned with the opening 13, and the valve 5 lowered into the discharge opening 4. When it is desired to permit unrestricted flow into the disposal conduit, the entire device is lifted out of the discharge opening.

What I claim is:

1. A disposal intake control comprising, an upper and a lower member seatable in a disposal intake opening, the lower member having an upper end and a lower end, a discharge opening at its lower end and an outwardly projecting flange on the upper end thereof, a resilient sealing member mounted on said flange, internal threads in an upper wall of said lower member adjacent and inwardly of said flange, said upper member having a lower rim and external threads adjacent said rim adapted to be received by the said internal threads of said lower member, a plurality of drain openings in said upper member and a valve loosely mounted in said upper member and adapted to seat in the discharge opening in said lower member said upper member and said lower member each being fundamentally hemispherical in shape and joining together by said internal and said external threads to form an essentially ball-shaped control unit.

2. The device defined by claim 1 wherein there is a squared opening in said upper member, said valve having a valve stem, the upper portion of said stem being squared and being adapted to fit through said squared opening in said upper member.

3. The device defined in claim 1 wherein said resilient sealing member consists of an annular member having an internal annular slot in which the flange of said lower member is mounted.

4. The device defined in claim 1 wherein said discharge opening in the lower member is inwardly tapered and forms a valve seat, the outer periphery of said valve being inwardly and downwardly tapered to form a close fit in said seat.
